CONTACT MECHANISM FOR CIRCUIT
BREAKERS

Fritz Driescher, Jr., Moosburg, Germany

Application November 4, 1952, Serial No. 318,709

Claims priority, application Germany
March 11, 1952

6 Claims. (Cl. 200—146)

1

The present invention relates to contact mechanisms for circuit breakers, and more particularly to mechanisms of this character which include an arcing chamber where an explosion accompanying the interruption of a heavy current may safely take place, and in which any burning of the main contacts is avoided.

Generally the invention comprises a contact mechanism which includes a pair of main contacts and a pair of auxiliary contacts which auxiliary contacts open only after opening of the main contacts has been completed, all arcing taking place between the auxiliary contacts. The auxiliary contacts are enclosed in an arcing or explosion chamber which is divided into compartments the individual compartments being closed off automatically as the arcing between the auxiliary contacts progresses and the arcing path becomes longer. Preferably, the main contacts and auxiliary contacts are disposed within a unitary housing formed of suitable insulating material.

Among the objects of the invention, is the provision of a circuit breaker contact mechanism of this character in which all arcing accompanying the interruption of a heavy current takes place between a pair of auxiliary contacts which, at the time of the current interruption, are enclosed in a special arcing or explosion chamber.

A further object of the invention is the provision of a mechanism of this character in which the explosion chamber is partitioned into individual compartments.

Another object of the invention is the provision of means for automatically closing off and isolating the individual compartments of the arcing chamber so that the arc is positively extinguished.

Still another object of the invention is the provision of telescopic spring means for preventing the opening of the auxiliary contacts until after the main contacts have opened.

Other and further objects will become apparent upon reading the following specification together with the accompanying drawing forming a part hereof.

Referring to the drawing, the single figure is a diagrammatic representation of an embodiment of the invention illustratively shown as a sectional view in elevation.

In the drawing, a movable main contact 1 is shaped as a pointed rod and is movably disposed within a chamber 2 of a housing which is made of suitable insulating material. The movable contact 1 is shown in engagement with a stationary contact 3 indicated by way of example as contact springs disposed within the chamber 2.

Immediately beneath the main contact chamber 2 is an auxiliary contact chamber 4 in which all arcing and any incidental explosions take place. Movable disposed within the auxiliary

2

contact chamber 4 is a headed movable auxiliary contact pin 5 having a neck portion immediately behind the head 7. The neck portion of auxiliary contact pin 5 is held by an annular stationary contact spring 6, thus requiring a predetermined minimum force to effect withdrawal of the head 7 of the movable contact pin 5 from engagement with the stationary annular contact spring 6. Other forms of auxiliary stationary contact may be used instead of the annular contact spring 6, provided there is a predetermined minimum force required to effect disengagement of the movable auxiliary contact from the stationary auxiliary contact.

15 The auxiliary contact chamber 4 is provided with an intermediate wall 8 which divides the contact chamber 4 into two compartments. The auxiliary contact chamber 4 is also provided with an end wall 9. The intermediate wall 8 has an aperture 8' therein and the end wall 9 has an aperture 9' therein through which the auxiliary contact pin 5 passes freely.

The auxiliary contact pin 5 is secured through a telescopic spring unit 10 to the main movable contact supporting member 11. After a predetermined movement of the main movable contact supporting member 11 toward the left as viewed in the drawing, a sufficient force is produced by compression of the helical springs in the telescopic spring unit 10 to effect disengagement of the movable auxiliary contact pin 5 from the stationary annular auxiliary contact spring 6.

25 Each of the openings 8' and 9' is provided with a self-closing flap 12 and 13, respectively. When the auxiliary contacts 5—6 are closed, the flaps 12 and 13 are in the positions indicated in solid lines, and when the auxiliary contacts 5—6 open, the flaps 12 and 13 swing through the arcs indicated in dotted lines to close the apertures 8' and 9', respectively. Instead of the gravity actuated flaps 12 and 13, positively controlled closure means may be utilized, such as rotary gates or doors, for example.

30 The main contacts 1—3 and the auxiliary contacts 5—6 are electrically connected in parallel.

35 The main movable contact supporting member 11 may be moved manually, or it may be actuated by any desired conventional and well known form of circuit breaker mechanism. This 40 has been illustratively indicated in the drawing as a vertically movable pin 14 which is moved downwardly to trip the breaker. Pin 14 engages a rotary lever 15 which forces a horizontal pin 16 to the right against a compression spring 17.

45 A rod 18 is pivoted to horizontal pin 16 and is mechanically arranged to actuate the tripping mechanism of the circuit breaker which is of conventional construction and which has therefore been omitted from the drawing.

50 In operation, upon tripping of the breaker, the main contact supporting member 11 moves to the

left to the position indicated in dotted lines. In moving to the left the main contacts 1-3 open immediately and a force tending to open the auxiliary contacts 5-6 is developed by compression of the springs within the telescopic spring unit 10. The annular contact spring 6, however, holds the head 7 of auxiliary movable contact pin 5 until sufficient force is developed within the telescopic spring unit 10 to effect disengagement of the head 7 from the annular spring 6. When this occurs, the auxiliary movable contact pin 5 is snapped rapidly to the left, and as it is withdrawn successively through the apertures 8' and 9' in the walls 8 and 9, respectively, the doors 12 and 13 swing to their closed positions. Closure of the doors 12 and 13 extinguishes the arc and seals off the arcing or explosion chamber 4, dividing it into two separate isolated compartments.

It should be noted that a plurality of arcing or explosion chambers may be provided if desired, and that each such chamber may be divided into three or more compartments instead of two, if this is deemed to be desirable.

Having thus described my invention, it will be apparent to those skilled in the art that many changes and modifications may be made in the details thereof without departing from the scope of the invention as defined in the appended claims.

I claim:

1. Circuit breaker mechanism of the class described, comprising: a main stationary contact; a main movable contact engageable with said main stationary contact; a main movable contact supporting member upon which said main movable contact is supported; an apertured arcing chamber; an auxiliary stationary contact disposed within said arcing chamber; an auxiliary movable contact connected with said main movable contact and freely movable through said aperture into and out of said arcing chamber for engagement with said auxiliary stationary contact; closure means responsive to withdrawal of said movable auxiliary contact from said arcing chamber for closing said aperture; and delaying means effective during the opening of said main contacts for causing said auxiliary contacts to remain closed until after said main contacts have opened, said delaying means comprising spring means connecting said movable auxiliary contact to said supporting member, said two auxiliary contacts further comprising means for opposing the opening of said auxiliary contacts until a predetermined minimum force tending to open said auxiliary contacts has been produced in said spring means by movement of said supporting member.

2. Contact mechanism according to claim 1, wherein said spring means comprises a telescopic spring unit.

3. Contact mechanism according to claim 1, wherein said means for opposing the opening of said auxiliary contacts comprises a head portion of one of said auxiliary contacts in engagement with an annular spring portion of the other contact, said minimum force being required to withdraw said head from said annular spring.

4. Circuit breaker contact mechanism of the class described, comprising: a main stationary contact; a main movable contact engageable with said main stationary contact; an apertured arcing chamber; an auxiliary stationary contact disposed within said arcing chamber; an auxiliary movable contact connected with said main mov-

able contact and freely movable through said aperture into and out of said arcing chamber for engagement with said auxiliary stationary contact; closure means responsive to withdrawal of said movable auxiliary contact from said arcing chamber for closing said aperture; an apertured partition within said arcing chamber dividing said chamber into a plurality of compartments, said movable auxiliary contact being freely movable through said partition aperture; closure means responsive to withdrawal of said movable auxiliary contact through said partition aperture to close said aperture and isolate said compartments from each other; and delaying means effective during the opening of said main contacts for causing said auxiliary contacts to remain closed until after said main contacts have opened.

5. Circuit breaker contact mechanism of the class described, comprising: a main stationary contact; a main movable contact engageable with said main stationary contact; an apertured arcing chamber; an auxiliary stationary contact disposed within said arcing chamber; an auxiliary movable contact connected with said main movable contact and freely movable through said aperture into and out of said arcing chamber for engagement with said auxiliary stationary contact; a gravity actuated flap responsive to withdrawal of said movable auxiliary contact from said arcing chamber for closing said aperture; and delaying means effective during the opening of said main contacts for causing said auxiliary contacts to remain closed until after said main contacts have opened.

6. Circuit breaker contact mechanism of the class described, comprising: a main stationary contact; a main movable contact engageable with said main stationary contact; an apertured arcing chamber; an auxiliary stationary contact disposed within said arcing chamber, said auxiliary stationary contact comprising an annular spring; an auxiliary movable contact connected with said main movable contact and freely movable through said aperture into and out of said arcing chamber for engagement with said stationary contact, said auxiliary movable contact comprising a headed pin, the head of said pin being engageable with said annular spring to resist the withdrawal of said head therefrom; closure means responsive to withdrawal of said movable auxiliary contact from said arcing chamber for closing said aperture; and delaying means effective during the opening of said main contacts for causing said auxiliary contacts to remain closed until after said main contacts have opened, said delaying means comprising spring means effective after opening of said main contacts and disposed to exert a force tending to open said auxiliary contacts, said force being sufficient to withdraw said head of said pin from said annular spring.
